(57) **CLAIM**

The ornamental design for an electronic device with a graphical display element, as shown and described.

DESCRIPTION

FIG. 1 is a front view of an electronic device with a graphical display element; and,

FIG. 2 is a front view thereof, shown without the broken lines illustrating the text and various portions of the graphical display element.

The broken line showing of the electronic device in all the figures and the broken line showings of the text and various portions of the graphical display element in FIG. 1 form no part of the claimed design.

1 Claim, 1 Drawing Sheet
